US00D920339S

(12) **United States Design Patent** (10) Patent No.: **US D920,339 S**
(45) Date of Patent: **** May 25, 2021**

(54) **SUPPORT FOR COMPUTER TERMINALS**

(71) Applicant: **LEOMO, Inc.**, Boulder, CO (US)

(72) Inventors: **Kunihiko Kaji**, Tokyo (JP); **Satoru Taniyama**, Tokyo (JP)

(**) Term: **15 Years**

(21) Appl. No.: **35/508,516**

(22) Filed: **Aug. 1, 2019**

(80) **Hague Agreement Data**

Int. Filing Date: **Aug. 1, 2019**

Int. Reg. No.: **DM/204887**

Int. Reg. Date: **Aug. 1, 2019**

Int. Reg. Pub. Date: **Feb. 28, 2020**

(57) **CLAIM**

The ornamental design for a support for computer terminals, as shown and described.

DESCRIPTION

1. Support for computer terminals

1.1 : Front

1.2 : Right

1.3 : Back

1.4 : Left

1.5 : Top

1.6 : Bottom

1.7 : Perspective

1.8 : Perspective
